US00D859463S

(12) United States Design Patent (10) Patent No.: US D859,463 S
Chen et al. (45) Date of Patent: * Sep. 10, 2019

(54) DISPLAY SCREEN OR PORTION THEREOF WITH ICON

(71) Applicant: Apple Inc., Cupertino, CA (US)

(72) Inventors: Kevin Will Chen, Sunnyvale, CA (US);
Alan C. Dye, San Francisco, CA (US);
Jonathan P. Ive, San Francisco, CA (US); Christopher Wilson, San Francisco, CA (US)

(73) Assignee: Apple Inc., Cupertino, CA (US)

() Term: 15 Years

(21) Appl. No.: 29/627,105

(22) Filed: Nov. 22, 2017

Related U.S. Application Data

(63) Continuation of application No. 29/602,870, filed on May 4, 2017, now Pat. No. Des. 803,879, which is a continuation of application No. 29/565,411, filed on May 20, 2016, now abandoned, which is a continuation of application No. 29/534,857, filed on Jul. 31, 2015, now Pat. No. Des. 757,084, which is a continuation of application No. 29/501,230, filed on Sep. 2, 2014, now Pat. No. Des. 735,754.

(57) CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with icon showing the claimed design.

The broken lines in the FIGURE show a display screen or portion thereof, and form no part of the claimed design.
